Primary Examiner—Prabhakar Deshmukh*(74) Attorney, Agent, or Firm*—Jenkens & Gilchrist(57) **CLAIM**

The ornamental design for a leak-resistant polymeric foam container, as shown.

DESCRIPTION

FIG. 1 is a perspective view of a container in a closed position;

FIG. 2 is a top view of the container of FIG. 1;

FIG. 3 is a bottom view of the container of FIG. 1;

FIG. 4 is a first side view of the container of FIG. 1;

FIG. 5 is a second side view of the container of FIG. 1;

FIG. 6 is a third side view of the container of FIG. 1; and,

FIG. 7 is a fourth side view of the container of FIG. 1.
